PERMANENT MOLD

Melbourne A. Beckmann, Cincinnati, Ohio, assignor to Aluminum Industries, Inc., Cincinnati, Ohio, a corporation of Ohio

Application June 18, 1936, Serial No. 85,946

4 Claims. (Cl. 22—151)

The present invention relates to a permanent mold particularly adapted to cast pistons in aluminum alloys which pistons are described and shown in my co-pending applications, Serial 5 Numbers 79,309, 79,310 and 79,311, filed May 12, 1936.

The casting of pistons in permanent molds is complicated by the necessity of lifting out the cores bodily. In the ordinary piston, the pin 10 bosses are the only obstacle to lifting out such cores, but in the pistons here considered, the bridge forms an additional obstacle. The means provided for casting this bridge and for providing for the removal of the cores entire 15 from about and within the bridge form the subject matter of the invention. One of its objects is to provide such an arrangement of cores that a piston of my special kind can be produced expeditiously from a mold of the general 20 type described in the United States patent to Schnobrich, No. 1,525,893 of February 10, 1925. Another object is to provide means for keeping the thickness of the bridge metal in proper relation.

25 In the accompanying drawing, Figure 1 is a vertical cross section of the mold with all of the cores in place except the bridge core, which is shown above its proper place. The cores are shown in section along the line 1—1 of Fig. 4.

30 Figure 2 shows all of the cores except the piston pin cores, assembled, partly in section on the line 2—2 of Fig. 4.

Figure 3 is a perspective cross-sectional view 35 of a piston to be cast in my mold. The relation between Figures 2 and 3 is as if the cores of Figure 2 had first been pulled out of the piston of Figure 3, and reassembled immediately above.

Figure 4 is a cross section of the entire central 40 core assembly taken on the line 4—4 of Figure 2.

In Figure 1, 10 is the body of the mold, 11 is the floor and 12 is the mold cavity. This cavity is established in the form of an inverted internal combustion engine piston by a seven piece core 45 which may be considered to be composed of two kinds of pieces. These are the piston pin hole cores 13 which extend into the mold cavity from opposite sides, and the core pieces 17, 18, 19 and 21, shown assembled in Figure 2, which extend 50 vertically from above into the mold cavity. These are preferably five in number but may be more or less in some cases.

The depending cores are each provided with an upper flange 15 each of which is so shaped 55 as to fit and cooperate with the other flanges 15

to make a substantially closed mosaic over the mold cavity, except of course, for the pouring gates. These, being conventional are not shown, their arrangement being substantially as in United States Patent 1,585,893. Cores 13 are 5 also manipulated as in the patent referred to. Each core, except 13 is provided with an individual handle 16 for manual withdrawal.

Referring to Figure 4, the central core assembly comprises a core 17 of nearly rectangular 10 cross section. This is the largest core and the one which is last inserted and first withdrawn after casting. Flanking the core 17 there are two irregularly shaped side cores 18. Abutting all three of the just mentioned cores there is a 15 "butterfly core" 19, so called because its cross section looks from above like a butterfly minus the body. Another core 21, known as the bridge core, because its function is to help form the bridge 24, shown in Figure 3, is contained within 20 the butterfly core. Its upper portion 20 as seen in Figure 2, is completely encircled by the core 19 so that it is firmly positioned, but its lower end 21 hangs free so that the metal can flow 25 around it. Accurate control of the shape and thickness of the bridge is thus rendered possible because the core is aligned not only by the top flange 15 but also by a long bearing surface 20 cooperating with the core 19. The former controls the depth and the latter the alignment. 30 The core surfaces are all accurately machined in cast iron, so that close fitting is achieved.

In operation the cores 18 are inserted first in the empty mold; the piston pin hole cores 13 which form the piston pin holes 22 and the 35 bosses 23 around them are then brought into position. Core 19 is then inserted and the bridge core 21 slipped into it. Core 17 is now positioned and the casting performed.

After setting of the metal, core 21 is usually 40 first pulled, then cores 17 and 19, although core 17 may be pulled first; cores 18 can then be withdrawn by pulling them first to the middle of the mold cavity until they clear the bosses, then lifting upward.

45 By having the bridge core suspended in the butterfly core on a long, accurate bearing, even if the butterfly core should become somewhat misaligned in relation to cores 17 or 18, the bridge casting would still be strong and accurate 50 because no substantial displacement of core 21 in core 19 is possible.

I claim as my invention:

1. A permanent-mold structure for making an internal combustion engine piston which com- 55

- prises a mold body two piston pin hole cores extending into said mold body from opposite sides thereof, a five piece core extending vertically down into said mold body, one of said core pieces 5 being in plan, of butterfly shape and containing a second piece of the core, said latter piece being of rounded triangular shape, and held for a substantial portion of its length at a small distance from its containing core.
- 10 2. A permanent mold metal casting structure comprising a mold body and a multiple piece core fitting into said body, one of said core pieces containing another, said contained piece being held over a portion of its length at a distance 15 from its containing core, and being extractable therefrom so that said containing core may be withdrawn from the mold.
3. A mold core for a permanent mold metal

casting structure composed of at least two core pieces, one core piece being contained within the other and spaced therefrom over a portion of its length and being extractable therefrom so that said containing core may be withdrawn from the 5 mold.

4. A mold core for a permanent mold metal casting structure composed of at least two core pieces, one core piece being contained within the other and spaced therefrom over a portion of its length and being extractable therefrom so that said containing core may be withdrawn from the mold, a portion of said containing piece being cut out around said contained piece to permit molding material to flow therebetween. 10 15
